UNITED STATES PATENT OFFICE.

DOLPH B. CRAWFORD, OF CHICAGO, ILLINOIS.

PISTON.

1,416,795.

Specification of Letters Patent. Patented May 23, 1922.

Application filed August 16, 1920. Serial No. 403,784.

To all whom it may concern:

Be it known that I, DOLPH B. CRAWFORD, a citizen of the United States, residing at Chicago, in the county of Cook and State 5 of Illinois, have invented a new and useful Improvement in Pistons, of which the following is a specification.

This invention has relation to an internal combustion engine, and refers particularly 10 to a novel piston construction for such engine.

The primary object of my invention is the provision of an improved piston structure. More particularly my object is to introduce 15 resilient devices operating to increase the efficiency of the piston by urging the piston rings against the wall of the cylinder. To this end my invention consists in the combinations and advantageous features hereinafter fully described and illustrated in the accompanying drawings, of which:

Fig. 1 illustrates, in side elevation, a piston structure embodying the invention,

Fig. 2 is a plan view substantially in 25 agreement with Fig. 1,

Fig. 3 is a fragmentary view, on a large scale, illustrating portions of the preceding figures,

Fig. 4 shows the resilient devices removed 30 from the piston,

Figs. 5 and 6 illustrate a modified form of the invention, and

Figs. 7 and 8 show further modifications 35 the importance of which will hereinafter appear.

Referring in the first instance to Figs. 1, 2 and 3, the numeral 1 denotes a piston having a plurality of peripheral grooves 1^a, in which are seated a corresponding number 40 of piston rings 2. The latter may be of any well known construction and, of course, the more perfectly the ends of the rings are joined together, the less also the leakage past the joints of the rings. Within the 45 piston is placed a sleeve 3 provided with a plurality of radially disposed sockets 3^a, in which are seated a corresponding number of springs 4. It is noticed that a corresponding number of perforations 1^b are provided 50 in the grooves of the piston, and the sleeve 3 is so placed within the piston that said perforations register with the sockets 3^a. Slidably mounted in each perforation is a plunger 5 urged forward by the pressure 55 of the springs 4, and a disc may conveniently be placed between the spring and plunger, or

said spring and plunger may be made in one piece, if desired. The advantage of the separate disc and plunger is that less accuracy is required in positioning the sleeve relative to the perforations in the piston wall. On the other hand there is a distinct advantage in combining the parts, in that it retains the plungers in place when the piston ring is removed.

It is readily seen by anyone versed in the art that the springs 4 exert pressure against the inner periphery of the piston rings 2, thereby urging the latter outward in order to maintain said rings pressed against the cylinder wall of the engine (not shown). A well fitted piston in the cylinder of an internal combustion engine is always difficult to obtain in the common type of piston structure, in which the proper fit depends upon the resiliency of the piston ring itself combined with the expansion of said ring caused by the heat generated within the cylinder. If the ring is too loose a decided waste of fuel ensues, if too tight the friction created operates to reduce the power output, besides scoring and unduly wearing the walls of the cylinder. While in the common type of piston ring great care must be exercised to select the proper material, 85 I wish it understood that, in the structure of my invention, the material best adapted for reducing friction between the ring and cylinder wall may be adopted without paying attention to the aforesigned conditions. 90 This is a very important feature of my invention.

The springs 4, being housed within the sockets of the sleeve 3, are protected from flame and dirt. It is, however, desirable 95 that some small opening be provided, such as the perforations 3^b, through which the splashing oil may penetrate and thereby lubricate said springs. I have hereinbefore spoken of the sleeve as having one row of 100 spring sockets operating upon one piston ring, in which case one sleeve is required for each ring employed, but I wish it understood that one common sleeve may be used, said sleeve having sockets for registration with 105 the whole group of piston rings, if desired.

The sleeve structure hereinbefore described is desirable on account of the ease with which it may be assembled and put into position within the piston, yet it is 110 not always possible to employ such structure for the reason that some pistons are

made with internal strengthening ribs positioned in the path of insertion of the sleeve, whereas a smooth internal cylindrical surface is requisite in order to place the sleeve.

5 Reference is now invited to Figs. 5 and 6 which illustrate a means of applying the spring sockets directly to the piston without first mounting said sockets in a sleeve. The numeral 10 denotes a portion of the piston 10^a wall and shows the groove 10^a in which the piston ring 11 is seated. The piston has a series of perforations 10^b for accommodation of a corresponding series of plungers 12. The spring sockets in this case, as best 15 shown in Fig. 6, comprise a body portion 13 provided with diametrically opposite prongs 13^a, which in turn are seated in perforations 10^c of the piston. It is noticed that the ends of said prongs are riveted over in order to 20 retain the sockets firmly in place, but, of course, a spot welding or similar operation may be resorted to for this purpose. The springs 14 and discs 15 remain as described, and I wish to point out, that the plunger 25 and disc also in this case may be combined into one piece, if preferred.

The structure of Fig. 8 corresponds in a general way with the one just described. Specifically it is modified by eliminating the 30 plunger element entirely. In this case the perforations 20 of the piston wall are made large enough to accommodate the body portion of the sockets 21, and the latter, as best shown in Fig. 8, are made with a flange 21^a, 35 which in turn is recessed into a seat in the piston, in order that the face of said socket may be flush with the outer piston wall. It is clearly shown how the disc 22 is urged by the spring 24 against the piston 40 ring 23. Attention is called to a second series of sockets 25, said sockets positioned to register with the adjacent piston ring (not shown) and it is seen that the sockets 21 and the sockets 25 are placed in 45 staggered relation, which is done in order to retain the piston wall as strong as possible.

The devices hereinbefore described illustrate plainly the scope of my invention, but 50 the proportions and relations of the parts may, of course, be varied to suit conditions and in order to obtain the strongest and most

efficient structure under the circumstances. Also the number of spring sockets may be varied to suit individual conditions.

55

I claim:

1. The combination with the piston of an internal combustion engine and a piston ring, of means attachable to the piston for holding a plurality of spring-held plungers, 60 said plungers confined within the piston when the device is assembled and extending through the piston wall in order to exert pressure against said piston ring.

2. The combination with a piston provided with a series of radial perforations, and a piston ring seated in said piston, of a sleeve carrying a series of spring-held plungers seatable in said perforations, said sleeve insertable within the piston when the 70 plungers are depressed, but incapable of detachment when said plungers have entered the said piston perforations.

3. In the piston of an internal combustion engine, a sleeve structure mounted with in said piston and having resilient members for urging the rings of the piston against the inner wall of the engine cylinder.

4. In the piston of an internal combustion engine, said piston provided with a series of radial perforations, the combination with the piston rings, of a sleeve fitted within the piston, said sleeve perforated to receive a corresponding series of plungers seated in said perforations, resilient members urging said plungers against the inner periphery of said piston rings, and devices for maintaining said resilient members in position.

5. In a piston for an internal combustion engine, a sleeve fitting the inner wall of said piston and provided with series of staggered housings registering with perforations of the piston wall, springs within said housings, plungers in said perforations and abutting the rings of the piston, and discs between said plungers and springs, said discs of larger diameter than the plungers in order to allow for inaccuracies of placing the parts.

In testimony whereof I have hereunto affixed my signature.

DOLPH B. CRAWFORD.
